CATALYTIC DISTILLATION OF SHALE

Robert W. Krebs, Baton Rouge, La., assignor to
 Standard Oil Development Company, a corpora-
 tion of Delaware

Application June 11, 1947, Serial No. 754,028

12 Claims. (Cl. 202—6)

1

The present invention relates to the art of distilling carbonizable solids. More particularly, the present invention relates to a novel process for the recovery of valuable volatile fuels such as combustible gases, motor fuels, heating and fuel oils from oil-bearing minerals such as oil shale, oil sands, tar sands, and the like.

It is known that certain types of naturally occurring oil-bearing minerals, such as oil shale, contain materials which may be converted by a pyrolytic treatment into hydrocarbon oils, including oils boiling in the gasoline and gas oil ranges, in commercially feasible yields.

Prior to the present invention, others proposed carrying out the pyrolytic treatment of the shale in the form of a powder or rather large aggregates of up to about $\frac{1}{4}$ in. diameter, in a highly turbulent state, fluidized by an upwardly flowing gas, in a distillation or pyrolytic zone, while supplying the heat necessary for the reaction by combustion, that is, either by burning a portion of the combustibles in the distillation or pyrolytic zone, or by burning the spent shale in a separate combustion zone and returning the burnt substantially uncooled shale to the distillation or pyrolytic zone. The former method has the advantage of a simple design while the latter method permits the production of oil free of gaseous combustion products. However, all these processes have marked disadvantages.

It is a matter of record that oil shale disintegrates rapidly in the process of distillation to form powders of extremely small particle size, substantially independent of the particle size at which the shale is supplied to the distillation zone initially. The disintegrated shale powder is so fine that it seriously interferes with the maintenance of proper fluidization conditions which normally require a relatively low percentage of say, less than 20%, of particle sizes below 20 microns. However, the oil shale powder formed during distillation has a particle size generally below 40 and mostly below 20 microns which results in channelling and slugging thus vitiating most of the advantages of fluid operation such as perfect heat distribution and transfer, etc.

The product recovered from conventional shale distillation processes consists predominantly of gas oils and higher boiling hydrocarbons. Straight-run gasoline is produced in poor yields and relatively poor quality. Particularly the octane rating and volatility distribution are unsatisfactory, in comparison with the corresponding characteristics of cracked gasolines.

The present invention has for its principal object the improvement of fluid oil shale or oil sand distillation processes with respect to both fluidity characteristics and gasoline yields and quality.

2

In accordance with the present invention, finely divided oil-bearing minerals of the type specified are subjected to distillation in the form of a dense, turbulent, fluidized mass of solids in the presence of a finely divided conventional cracking catalyst having a particle size substantially larger than the particle size of the oil-bearing mineral after disintegration during the distillation process. The amounts of relatively coarse cracking catalyst are so chosen that the particle size distribution of the fluidized solids phase is maintained within well-fluidizable ranges and that substantial cracking of gas oil range and heavier hydrocarbons into gasoline range products takes place.

Well fluidizable particle size ranges may fall within the approximate limits given below:

	Per cent
0-20 microns	less than 20
20-40 microns	10-25
40-80 microns	20-30
80+ microns	25-35

While the above size distribution is preferred and affords excellent fluidization, it should be understood that good fluidization may be obtained at different distributions provided that fine and coarse sizes are properly adjusted. For example, the particles of less than 20 microns may amount to as much as about 50% if sufficient amounts of particles of intermediate ranges, say of 20-80 microns size, are present. A substantial proportion of the particles above 20 micron size required for proper fluidization will normally be present in the form of fresh process solids which may be charged in desirable sizes and which maintain their original size for a limited length of time.

The cracking catalyst becomes rapidly deactivated mainly due to the formation of carbon which deposits on the catalyst. As a result of the larger particle size of the catalyst, deactivated carbonized catalyst may be readily separated from the finer particles of the treated mineral, by taking advantage of the difference in gas buoyancy of the particles to be separated. The carbonized and separated catalyst may be regenerated in a conventional fluid regeneration zone by a combustion reaction with an oxidizing gas and returned to the distillation zone. In this manner, heat generated by the combustion reaction may be supplied to the cracking-distillation zone as sensible heat of the catalyst, a procedure which is known per se in the art of catalytic cracking.

The amount of catalyst required in the distillation zone and in circulation between the distillation and regeneration zones will therefore depend on the particle size distribution within the fluid distillation zone, the particle size, specific gravity and cracking activity of the cat-

alyst, and the amount of heat which it is desired to supply to the distillation zone as sensible heat of regenerated catalyst. It will be appreciated that this amount of catalyst may vary within fairly wide ranges. Quite generally, it may be stated, however, that when using such conventional cracking catalysts as Super Filtrol (which is a bentonite clay, containing largely hydrated aluminum silicates, which have been acid treated), silica-magnesia catalyst containing 30-35% magnesia, or silica-alumina catalysts containing 10-20% alumina, preferably in the form of microspheres, in particle sizes of about 50-500 microns and assuming a disintegrated particle size of the process solids of less than 40 microns and a crackable oil content of the process solids of about 0.3-1.0 bbl. per ton, an amount of about 10% to 400% of circulating catalyst based on process solids, is usually adequate depending on the proportion of heat supply desired in the form of sensible heat of catalyst. For example, the amount of circulating catalyst may be about 20-100% by weight of a shale containing about 0.5 bbl. of crackable oil per ton. The proportion of catalyst in the distillation zone itself may fall within similar ranges. Any additional heat required may be supplied as preheat of solid and/or gaseous process materials and/or by conducting a limited combustion within the distillation zone itself.

Separation of coarse catalyst from process solids fines may be readily accomplished by so controlling the superficial velocity of the fluidizing gas within the distillation zone that process solids fines are fully entrained and carried overhead by the fluidizing gas while the disintegration of coarse catalyst is insignificant and it remains in the distillation zone as a dense fluidized solids phase from which it may be withdrawn downwardly and separately from the fines as a stream of fluidized solids. Superficial gas velocities of about 0.5-3 ft. per second, preferably about 1 ft. per second are normally adequate at the particle size distribution indicated above.

The temperatures in the distillation zone may be those usually employed in the distillation of oil shales, that is about 800°-1100° F. These temperatures are simultaneously conducive to appreciable catalytic cracking of gas oil and heavier hydrocarbons at relatively low pressures of atmospheric to about 10 atmospheres. Catalyst regeneration is preferably carried out at slightly higher temperatures, say about 100°-200° F. higher, and at substantially atmospheric pressure.

It will be appreciated from the foregoing that the present invention affords substantial improvements with respect to both fluidization control and gasoline yield. Simultaneously, the gasoline quality is considerably improved as a result of the beneficial influence of the catalytic cracking reaction on octane rating and volatility distribution.

Having set forth its general nature and objects the invention will be best understood from the more specific description hereinafter wherein reference will be made to the accompanying drawing the single figure of which is a partly schematic, partly diagrammatical illustration of a system suitable for carrying out a preferred embodiment of the invention.

Referring now in detail to the drawing the 75

system illustrated therein essentially comprises a cracking-distillation chamber 15 and a regenerator-combustion chamber 45 the functions and cooperation of which will be forthwith described using as an example the treatment of an oil shale containing about 0.5 bbl. of oil constituents per ton. It should be understood, however, that other oil-bearing minerals may be treated in a substantially analogous manner.

10 In operation, feed hopper 1 contains fresh oil shale crushed to a particle size of about 50-100 microns, which may be dried and preheated, preferably in heat exchange with hot product or flue gases, to a temperature of about 400°-700° F. 15 The preheating gases may be supplied through lines 3 to serve simultaneously as aeration gases maintaining the shale feed in a readily flowing, quasi-fluid state. Fresh preheated finely divided shale flows from hopper 1 downwardly through a conventional standpipe 5 aerated through one or more taps 6 with small amounts of steam or flue gas to facilitate the solids flow which may be controlled by slide valve 8.

Fresh shale discharges under the pseudo-hydrostatic pressure of standpipe 5 into line 10. Simultaneously, a gas is supplied to line 10 which may be an inert or a free oxygen-containing gas such as air or air diluted with steam or flue gas, preheated preferably by heat exchange with hot product or waste gases or solids, to a temperature of about 800°-1200° F. The fresh shale is suspended in this gas to form a relatively dilute suspension which is forced under the pressure of standpipe 5 upwardly through pipe 12. 35 The suspension enters chamber 15 through a conical distributing device 13 provided with a perforated cover plate such as a grid 14.

Chamber 15 contains a mass of finely divided cracking catalyst such as Super Filtrol clay having a particle size larger than 50 microns, say about 100-500 microns. The bulk of this catalyst may be supplied to chamber 15 from feed hopper 1 in the initial stages of the process substantially as described above in connection with the fresh shale feed. Make-up catalyst may be continuously or periodically supplied together with the fresh shale as required. The dimensions of chamber 15, the superficial velocity of the gas supplied through line 12 and the amount of catalyst are so correlated that the combined catalyst and fresh shale particles form a dense, highly turbulent mass 17 of fluidized solids having a well defined upper level L₁₅ and providing for an average shale residence time within said dense mass of about 0.5-5 minutes, preferably about 1-3 minutes. Superficial gas velocities within the range of about 0.5-3 ft. per second and a catalyst to fresh shale weight ratio of about 0.5 to 1, are generally suitable for this purpose.

The temperature within chamber 15 is maintained preferably at about 800°-1000° F. This may be accomplished either by sufficiently pre-heating the process solids and gases as indicated above or by conducting a limited combustion of combustible shale constituents within mass 17 or by supplying suitable proportions of hot regenerated catalyst from regenerator 45 as will appear more clearly hereinafter, or by any suitable combination of these heating means. For example, temperatures of the range specified may be maintained by preheating the shale to about 600° F., preheating the gas in line 10 to about 1000° F., supplying about 0.1 to 0.2 mols of oxygen

and about 1000 to 2000 normal cu. ft. of total gas through line 12 and recycling about 1 ton of regenerated catalyst having a temperature of about 1100°-1200° F. from regenerator 45, per ton of shale to be treated. The pressure within chamber 15 is preferably maintained at about 3 to 30 lbs. per sq. in. gauge.

At the conditions specified the shale undergoes rapid distillation and disintegration. After, say, about half of its total residence time in mass 17 the shale particles may have disintegrated to an average particle size smaller than that of the catalyst, to be reduced to sizes below 20 microns during the remainder of the residence time. The oil evolved during this transformation is cracked into predominating proportions of gasoline. At the prevailing gas velocities a substantially complete separation of catalyst and substantially spent shale fines having particle sizes below 20 microns is accomplished, the shale fines being carried as gas entrainment upwardly beyond level L₁₅ and the larger catalyst particles which are not subject to disintegration remaining within mass 17.

Volatile cracking and distillation products and entrained spent shale fines are withdrawn overhead from level L₁₅ and passed through line 19 to a gas-solids separation system 21, 23 which may comprise conventional centrifugal and/or electric precipitators. Volatile products are withdrawn through line 25 and passed to a conventional product recovery (system not shown). Separated spent shale fines are collected in vessel 27. Their sensible heat may be used substantially at the temperature of chamber 15 to preheat process gases, using any suitable conventional means of heat exchange. Spent shale may be finally removed through line 29. Its residual carbon content is available for fuel purposes, for example to generate steam used in the process.

As a result of the extensive cracking taking place in chamber 15 the cracking catalyst becomes deactivated by carbon deposition and must be regenerated. For this purpose catalyst is withdrawn from the lower portion of chamber 15, preferably from a point below distributing device 13 through a conventional standpipe 35 aerated through one or more taps 37 and provided with slide valve 39. In order to prevent spent shale particles of smaller than catalyst size from entering pipe 35 additional amounts of fluidizing gas may be supplied through lines 31 to the annular space 33 formed by cone 13 and chamber 15, so as to exert an elutriating effect on the solids in annular space 33. The fluidizing gas supplied through lines 31 may simultaneously act as a stripping gas to remove adhering valuable volatiles from the catalyst prior to its removal from chamber 15.

Deactivated catalyst which normally includes only insignificant amounts of shale particles of similar size flows under the pseudo-hydrostatic pressure of standpipe 35 through control valve 39 into pipe 41. An oxidizing gas such as air and/or oxygen, preferably preheated in heat exchange with process flue gases to about 800°-1000° F. is supplied to line 41 and carries the spent catalyst as a dilute suspension upwardly into regenerator 45 through a distributing device 43 similar to device 13, under the pressure of standpipe 35. The amount of oxygen supplied through line 41 should be sufficient to remove about 80-100% of the carbon on the catalyst by combustion. About 0.5 to 5 mols of oxygen per ton

of shale treated is usually sufficient for this purpose.

The catalyst-in-gas suspension enters regenerator 45 at a superficial gas velocity of about 0.5-3 ft. per second to form a dense fluidized solids mass 47 therein, similar to mass 17. The temperature within mass 47 is preferably maintained at about 1000°-1200° F. by any conventional cooling means (not shown). Higher temperatures may be employed if they have no adverse effect on the catalyst. Hot flue gases which contain some entrained catalyst are withdrawn overhead from level L₄₅ and passed to a gas solids separator such as a cyclone 49. Flue gases free of solids are withdrawn through line 51 to be used for heat exchange with process gases and solids as described above. Separated catalyst may be returned to mass 47 through line 52 and catalyst particles of undesired small size may be discarded through line 53.

Regenerated catalyst is withdrawn downwardly from regenerator 45 through a conventional standpipe 55 aerated through taps 56 and provided with control valve 57. The solids flow from regenerator 45 may be facilitated by injecting small amounts of fluidizing gas such as air into annular space 52 through taps 54. Catalyst from standpipe 55 discharges under the pressure of this standpipe into line 59 wherein it is taken up by a carrier gas which may be an inert or combustion supporting gas similar to that supplied to line 19 and preheated to about the same temperature. The catalyst suspension in line 59 is passed substantially at the temperature of regenerator 45 to line 12 and from there to chamber 15, to complete the cycle. As previously stated the amount of catalyst circulating through lines 35, 41, 55 and 59 should be about 0.2 to 1 ton per ton of fresh shale treated at the conditions indicated.

The system illustrated by the drawing permits of various modifications. Instead of supplying fresh shale through standpipe 5 and gas-suspension line 12 to the bottom portion of chamber 15 it may be desirable in many cases to charge the fresh shale to the top of chamber 15, for instance by gravity from a hopper 60 through line 61. This arrangement is of particular advantage when substantial amounts of heat are to be generated by combustion within chamber 15. When feeding the combustion supporting gas to the bottom and the fresh shale to the top of chamber 15 a slight degree of counter-current flow of solids and gases is accomplished resulting in the contact of the combustion-supporting gas predominantly with carbonized rather than with fresh shale whereby excessive losses of valuable volatiles by combustion are avoided. If the amount of carbon deposited on the catalyst is insufficient to generate the desired amount of heat by combustion in regenerator 45 additional fuel in the form of a fuel gas or, preferably, in the form of shale circulated from still 15 may be supplied to regenerator 45. Instead of using standpipes 5, 35 and 55 other conventional means for conveying finely divided solids such as lock hoppers, mechanical conveyors, etc. may be employed. The process of the invention may be conducted in a fully continuous manner by continuously charging process solids and gases, continuously withdrawing product vapors and solids and continuously circulating the catalyst as indicated. Other modifications may occur to those skilled in the art.

It will be understood that the gasoline yields obtainable by the process of the invention depend largely on the starting material used and the

specific conditions applied. Quite generally the invention may permit an increase of about 50-100% in the straight-run gasoline yield as compared with conventional operation. The octane number of this gasoline may reach 60-75 by the research method as compared with about 40-55 in conventional operation.

While the foregoing description and exemplary operations have served to illustrate specific applications and results of the invention, other modifications obvious to those skilled in the art are within the scope of the invention. Only such limitations should be imposed on the invention as are indicated in the appended claims.

I claim:

1. In the method of distilling oil-bearing minerals which tend to disintegrate upon distillation, to produce therefrom volatile products rich in gasoline-range constituents by subjecting the finely divided starting material to distillation temperatures in a dense turbulent mass of finely divided solids fluidized by an upwardly flowing gas in a distillation zone, the improvement which comprises admixing with said material undergoing distillation a relatively disintegration resistant cracking catalyst having a particle size substantially larger than 50 microns, the particle size of said material after distillation being substantially smaller than 50 microns and amounting to less than about 60% by weight of said mass so as to maintain a well fluidizable particle size distribution in said mass, recovering a gas-distillate mixture containing cracked gasoline from said distillation zone, and controlling the superficial velocity of said gas so that particles of said material disintegrated to said size reached after distillation are preferentially entrained and carried out of said mass by said mixture and catalyst particles are preferentially retained.

2. The process of claim 1 in which particles of less than 20 microns size within said mass amount to less than 50% by weight of said mass.

3. The process of claim 2 in which the superficial velocity of said gas is about 0.5-3 ft. per second.

4. The process of claim 1 in which said temperature is about 800°-1000° F.

5. The process of claim 1 in which said gas contains oxygen supporting a limited combustion within said distillation zone and said material is charged to said distillation zone counter-currently to said gas.

6. The process of claim 1 in which said material is oil shale.

7. The process of claim 1 in which the particle size of said catalyst is about 100-500 microns.

8. In the method of distilling oil-bearing minerals which tend to disintegrate upon distillation, to produce therefrom volatile products rich in gasoline-range constituents by subjecting the finely divided starting material to distillation temperatures in a dense turbulent mass of finely divided solids fluidized by an upwardly flowing gas in a distillation zone, the improvement which comprises admixing with said material undergoing distillation a relatively disintegration resistant cracking catalyst having a particle size substantially larger than 50 microns, the particle size of said material after distillation being substantially smaller than 50 microns and amounting to less than about 60% by weight of said mass so as to maintain a well fluidizable particle size distribution in said mass, recovering a gas-distillate mixture containing cracked gasoline from said distillation zone, and controlling the superficial velocity of said gas so that particles of said material disintegrated to said size reached after distillation are preferentially entrained and carried out of said mass by said mixture and catalyst particles are preferentially retained, withdrawing solids consisting predominantly of catalyst from said mass separately from said material and said mixture, passing said withdrawn solids to a regeneration zone, contacting said withdrawn solids in said regeneration zone with a combustion-supporting gas to burn off carbon from said catalyst and to regenerate said catalyst, and returning said regenerated catalyst to said distillation zone.

9. The process of claim 8 in which said regeneration zone is maintained at a temperature substantially higher than said distillation temperature and said catalyst is returned substantially at said higher temperature.

10. The process of claim 9 in which said catalyst circulating from said regeneration zone to said distillation zone amounts to about 10-400% by weight of said material subjected to distillation within the same time.

11. The process of claim 8 in which heat of the gaseous combustion products from said regeneration zone is transferred to said distillation zone.

12. A method of distilling oil-bearing minerals which tend to disintegrate upon distillation, to produce therefrom volatile products rich in gasoline-range constituents by subjecting the finely divided starting material to distillation temperatures in a dense turbulent mass of finely divided solids fluidized by an upwardly flowing gas in a distillation zone, which comprises admixing with said material undergoing distillation a relatively disintegration resistant cracking catalyst having a particle size of about 100-500 microns, said material after distillation having a particle size substantially smaller than 50 microns and amounting to less than about 60% by weight of said mass, so as to maintain a well fluidizable particle size distribution in said mass, preferentially entraining disintegrated particles of said material in said gas and preferentially retaining catalyst in said mass by maintaining the superficial gas velocity within said mass at about 0.5-3 ft. per second, removing a distillate containing cracked gasoline, fluidizing gas, and disintegrated particles overhead from said zone and separately removing solids consisting predominantly of catalyst from said mass.
